UNITED STATES PATENT OFFICE.

WILLARD T. WALKER, OF RACINE, WISCONSIN, ASSIGNOR TO WALKER MANUFACTURING COMPANY, OF RACINE, WISCONSIN, A CORPORATION OF WISCONSIN.

DESIGN FOR A DISPLAY STAND.

Application filed February 5, 1923. Serial No. 5,079. Term of patent 14 years.

To all whom it may concern:

Be it known that I, WILLARD T. WALKER, a citizen of the United States, residing in Racine, in the county of Racine and State of Wisconsin, have invented a new, original, and ornamental Design for Display Stands, of which the following is a specification, reference being had to the accompanying drawing, forming part thereof.

The figure is a perspective view of a display stand showing my new design.

I claim:

The ornamental design for a display stand, as shown.

WILLARD T. WALKER.
